UNITED STATES PATENT OFFICE.

FREDRIK GREWIN, OF NORRKOPING, SWEDEN, ASSIGNOR TO AMERICAN VOITH CONTACT COMPANY, INCORPORATED, OF NEW YORK, N. Y., A CORPORATION OF NEW YORK.

DRYING.

Application filed January 18, 1927, Serial No. 161,905, and in Sweden October 24, 1923.

This application is filed to replace and as a continuation in part of my copending application Serial No. 745,715 filed in the United States on October 24, 1924 and in 5 Sweden on October 24, 1923 and is to be considered as relating back thereto for common subject matter.

My invention relates to drying and more particularly to the drying of a web of sheet material such as paper, cardboard, pulp, etc., carried over a series of cylinders.

One purpose of my invention is to remove vapor given off by the material to be dried from the vicinity thereof to obtain 15 an effective drying. A further purpose is to eject vapor laden fluid from the vicinity of the material to be dried by means of a stream of fluid other than that ejected, the ejecting fluid thus avoiding contact to as 20 great a degree as is possible with the material to be dried. Still another purpose is to provide a drier for web material such as paper which gives a better product than has hitherto been obtained.

25 My invention consists, in one form, in a method and apparatus for drying wherein a thin current of fluid such as compressed air is directed at high speed parallel to the surface to be dried but at a somewhat substantial distance therefrom so that the current does not impinge upon the surface and a second fluid such as atmospheric air is caused, by the ejector action of the said current of fluid, to pass between said current and said surface to dry the surface. In another form, I induce atmospheric air into a high pressure stream of air within a directing tube and cause the pressure air and induced air to pass close to and parallel to drying surface at high speed.

40 Further objects and features and the advantages of my invention will be understood as the description proceeds which is to be taken in connection with the accompanying drawings of which:

Fig. 1 is a diagrammatic showing in elevation of a web drier illustrating a basic principle of my invention;

45 Fig. 2 is a plan view of the drier of Fig. 1 with the upper felt removed and with a part in section and showing means for heating and compressing the ejector fluid;

Fig. 3 is a section taken on line 3—3, Fig. 1;

Fig. 4 is one view of a practical embodiment of my invention;

Fig. 5 is an end elevation showing the relative arrangement of the cylinders and the compressed air ducts;

Fig. 6 is a section of a nozzle;

Fig. 7 is a view showing the nozzle of Fig. 8 positioned in a mixing member having adjustable ports for air;

Fig. 8 is a section on the line 10—10 of Fig. 9;

Fig. 9 is a section of a modified form of nozzle; and

Fig. 10 shows a shield arrangement for use with the present invention.

Referring more particularly to Fig. 1, 10 designates the upper set of drying cylinders 70 of a web drying machine and 11 designates the lower cylinders of the web drying machine, said cylinders having the web 12 passed around them. An upper felt 13 75 passes over the upper cylinders 10 and around idler rolls 14. A lower felt 15 passes around cylinders 11 and idler rolls 16.

The arrangement of the cylinders, the web and the felts provides a series of spaces 80 extending laterally of the web drying machine, some of these spaces 17 being formed between sides determined by the web, the lower cylinders 11 and the upper felt 13, while other spaces 18 are formed between 85 sides determined by the web, the upper cylinders 10 and the lower felt 15. The cylinders 10 and 11 are heated in known manner.

The web of material to be dried gives off 90 considerable moisture which tends to collect in the spaces 17 and 18. These spaces if unventilated would become pockets for a mixture of air, vapor and condensed water, through which the web of material has to pass. In order to remove the moisture 95 from the spaces 17 and 18 and prevent condensation of water, I provide a series of ejectors directed in opposite directions into alternate spaces. The ejectors comprise small mouth pieces 19 and 20 so formed as 100 to be able to direct a thin stream of fluid through the respective spaces without having the stream impinge upon the material to be dried. The ejector mouth pieces are

formed so that when supplied with fluid at relatively high pressure they eject a single narrow stream as indicated in Fig. 3 along substantially the center lines of the respective spaces. Fluid, preferably air, is supplied to the ejectors at such pressure that the air contains a relatively high speed in the mouth pieces and the ejected stream becomes continuous and straight.

10 In order to supply fluid to the ejectors, air conduits 21 and 22 (see Fig. 2) are arranged longitudinally, one along each side of the drying machine. To conduit 21 are connected mouth pieces 19 by means of upwardly extending conduits 23. To conduit 22 are connected mouth pieces 20 by means of upwardly extending conduits 24. Thus the ejectors comprising mouth pieces 19 are directed in one direction into one alternate 20 set of spaces 18 while the ejectors comprising mouth pieces 20 are directed into the other set of alternate spaces 17 in the opposite direction. By this means a more even drying of the web is obtained. Air is supplied to conduits 21 and 22 by means of compressor 25 driven by any suitable prime mover 26.

The air supplied to the ejectors is preferably preheated as for example by the arrangement indicated at 28 which includes a steam heating element 27 situated in an air chamber to which air is supplied from any desired source and from which heated air passes to compressor 25.

35 By directing a thin stream into a space, as above described, parallel to the surface to be dried or in such direction that the stream does not impinge upon the surface to be dried, an ejector action is obtained
40 which draws air from outside the space, between the stream and the surface to be dried, which air serves to dry the web and remove moisture. The stream withdraws moisture without necessitating that the
45 amount of air supplied for obtaining the ejector effect be large enough to be able to absorb all the moisture given off from the web.

If desired, mouth pieces 29 below felt 15
50 may also be used to dry the felt.

For purposes of illustration, in Fig. 2, the middle cylinder is broken away to show the stream below the same ejected from mouth piece 19.

55 Figs. 4 to 9 show the invention as applied in actual commercial use. The cylinders 10 and 11 are rotated by means of intermeshing gears 30, 31, suitably supported on a framework 32. Figs. 4 to 9 show forms of 60 apparatus for applying the invention to practice in preferred manner. In Fig. 4, 21 designates a supply conduit for air under high pressure corresponding to the like lettered conduit of Fig. 2. A series of pipes of which one is designated by reference

character 33 in Fig. 4 are branched off from conduit 21. At the end of pipe 33 is a nozzle 35, shown in section in Fig. 6. Nozzle 35 is curved and tapers to a small end opening 41 which passes through an end opening 44 in a mixing member 45 (Fig. 7) formed in part by the end of a straight directing tube or conduit 36. Conduit 36 has a series of slots 38 in the same near the nozzle end and a regulating sleeve 37 having a corresponding series of ports 39 surrounding conduit 36. Sleeve 37 may be rotated about conduit 36 to determine the extent of opening through slots 38 and ports 39. Thumb screw 40 serves to maintain sleeve 37 in proper adjusted position on conduit 36. As shown in Fig. 7, ports 39 are rhomboidal in form in order to facilitate close setting in conjunction with the rectangular slots 38; both the slots and the ports, however, may be of any form or size for properly effecting the desired regulation.

In operation, the heated compressed air enters each individual connecting pipe 33 from the main air conduits 21 and passes through the outlet nozzle 35 into the directing tube 36, additional air being drawn in through slots 38 and ports 39 to mingle with the ejector air for properly drying the sheet of paper, pulp, etc. Directing tubes 36 extend into spaces 17 beyond the edge of the web in order to prevent curling of the edge of the paper. In applying the invention to practice I extend the directing tubes beyond the edge of the web from about 16 to 20 inches.

Fig. 9 shows a modified type of nozzle adapted to be inserted into opening 44 and attached to a horizontally disposed conduit, should the arrangement of the drier as a whole necessitate such construction or make it advisable. 105

Fig. 10 shows diagrammatically a three tier drier equipped with ejectors 19, 20 according to the invention. I use a pressure of air of from 20 to 70 inches of water in my invention which causes a blast of very high velocity. This assures blowing the air and moisture clear through the machine. It causes a high speed current of hot gas out of the exhaust end of each space which would tend to travel out into the room and might injure operators. To divert the high velocity stream I place shields 50, 51 at the space outlets which are suspended from hoods 52 arranged above the drier cylinders. Shield 50 is formed to divert the stream into the hood. Suction on the hood aids the effect. These shields save heat in directing the issuing streams into the hood which can be taken up in preheaters.

Experiments have shown, that with my invention, moist air in a web drying machine can be completely removed and the

web dried fully and uniformly. By means of the invention, the capacity of a web drying machine can be considerably increased without increase of steam consumption.

6 On the contrary, with the invention it is possible to decrease the steam consumption.

My invention thus produces uniform drying of the whole of the web course, increase of capacity of the machine and reduced 10 steam consumption per unit of weight.

While I have described various forms of my invention, it is to be understood that I shall not be limited to the specific embodiments illustrated.

15 Having thus particularly described my invention, what I claim is:

1. In combination, a plurality of cylinders over which a web of material to be dried is carried, the cylinders and web forming 20 laterally extending spaces of uniform cross-section with open ends, and means to direct a single thin current of air at high speed through each of said spaces in direction substantially along the center 25 lines of said spaces.

2. In combination, a plurality of members over which a web of material to be dried is carried, the members and web forming spaces, an ejector directed into at least one 30 of said spaces and formed to direct a thin stream of fluid through said space without impinging on said web, and thereby to induce a second fluid to pass through said space between said stream and the web, and 35 means to supply air to said ejector.

3. That improvement in the art of drying a surface which consists in directing a thin current of fluid at high speed parallel to said surface at a distance therefrom so 40 that said current does not impinge upon said surface, and thereby causing a second fluid to pass between said current and said surface to dry the surface.

4. That improvement in the art of drying a web of material carried over members 45 arranged to form a space between parts of the web, which consists in directing a thin current of air through the space in such direction as to avoid impinging on the web and thereby causing a second current of air 50 to pass between the directed current and the web to dry the web.

5. In combination, a plurality of members over which a web of material to be dried is carried, the members and web forming 55 spaces with laterally extending sides and open ends and means to direct a single thin current of fluid of high velocity through each of said spaces in direction parallel to 60 said laterally extending sides.

6. In combination, a plurality of members over which a web of material to be dried is carried, the members and web forming 65 spaces, ejectors situated at the ends of the spaces and arranged to deliver a current of

fluid of high velocity into each of the spaces in direction so as to pass entirely through the spaces and not impinge upon the web and means to supply pressure fluid to said ejectors, so that a current of fluid other than 70 that discharged through the ejectors serves to dry the web.

7. In combination, a plurality of members over which a web of material to be dried is carried, the members and web forming 75 spaces with laterally extending sides and open ends, a plurality of small-mouthed ejector pipes, one directed into each of said spaces and formed to limit the spread of the stream of ejecting fluid expelled therefrom, each pipe being directed to discharge a single stream of fluid of high velocity through the space into which it is directed, parallel to said laterally extending sides, and means to supply air to said ejector 80 pipes.

8. In combination, a web drier comprising a plurality of members over which a web of material to be dried is carried, the members and web forming a series of spaces, 90 a series of ejectors positioned on one side of said drier and directed into one set of alternate spaces, a second series of ejectors positioned on the other side of said drier and directed into the other set of alternate 95 spaces and means to supply air to said ejectors.

9. In combination, a web drier comprising a plurality of members over which a web to be dried is carried, the members and web forming laterally extending spaces, a series of ejectors positioned on one side of said drier, and directed into one set of alternate spaces, said ejectors being formed to direct a thin stream of fluid through the 100 respective spaces without impinging on said web, and thereby to induce a second fluid through the spaces between said stream and the web to dry the web, a second series of ejectors positioned on the other side of said 105 drier directed into the other set of alternate spaces and means to supply air to said ejectors.

10. In combination, a plurality of members over which a web of material to be 110 dried is carried, the members and web forming spaces with laterally extending sides and open ends and means to direct thin currents of fluid through said spaces in direction parallel to said laterally extending sides and at 115 a substantial distance from said sides so that a different fluid than that of the currents may be induced between the currents and the laterally extending sides.

11. In combination, a plurality of cylinders over which a web of material to be dried is carried, the cylinders and web forming laterally extending spaces of uniform cross-section with open ends, means to direct a thin current of air at high speed through 120

each of said spaces in a direction substantially along the center lines of said spaces, and means permitting said thin current of air to induce the flow of a regulated quantity of additional air.

12. That improvement in the art of drying a surface which consists in directing a current of compressor air of high pressure parallel to said surface at a distance therefrom and parallel thereto and inducing atmospheric air to pass past said surface due to ejector effect of said current.

13. In combination, a plurality of members over which a web of material to be dried is carried, the members and web forming spaces, directing tubes extending into said spaces beyond the edge of the web, ejectors arranged to discharge into said directing tubes and means to supply fluid to said ejectors.

14. In combination, a plurality of members over which a web of material to be dried is carried, the members and web forming spaces, directing tubes having openings at both ends and extending into said spaces beyond the edge of the web, ejectors arranged to discharge into said directing tubes and to draw air through some of said openings and means to supply air at high pressure to said ejectors.

15. In combination, a plurality of mem-

bers over which a web of material to be dried is carried, the members and web forming spaces, directing tubes extending into said spaces beyond the edge of the web and having air openings, ejectors arranged to discharge into said directing tubes and to draw air through said openings, means to supply air at high pressure to said ejectors and means to regulate the supply of air.

16. A drier comprising, in combination, a series of cylinders for carrying a web of material to be dried, the cylinders and the web forming laterally extending spaces with open ends, a hood above said drier, ejectors situated at the ends of the spaces, means to supply air at high pressure to said ejectors and shields suspended from said hoods for directing streams issued from said ejectors into said hood.

17. In combination, a plurality of members over which a web of material to be dried is carried, the members and web forming spaces, ejectors extending into said spaces beyond the edge of the web and arranged to deliver a current of fluid of high velocity into each of the spaces and means to supply fluid to said ejectors.

In testimony whereof I hereunto affix my signature.

FREDRIK GREWIN.
